Primary Examiner — Ruth McInroy(74) *Attorney, Agent, or Firm* — QuickPatents; Kevin Prince(57) **CLAIM**

I claim the ornamental design for a barbecue trailer, as shown and described.

DESCRIPTION

FIG. 1 is a perspective view of a barbecue trailer, showing my new design;

FIG. 2 is a top plan view thereof;

FIG. 3 is a left-side elevational view thereof;

FIG. 4 is a right-side elevational view thereof;

FIG. 5 is a front elevational view thereof; and,

FIG. 6 is a rear elevational view thereof.

The broken lines in the figures depict environmental matter and form no part of the claimed design. The bottom plan view forms no part of the claimed design.
